UNITED STATES PATENT OFFICE.

IRA C. TERRY, OF ST. LOUIS, MISSOURI, ASSIGNOR OF ONE-HALF TO
ANDREW WARREN, OF SAME PLACE.

CAR-TRUCK.

SPECIFICATION forming part of Letters Patent No. 278,292, dated May 22, 1883.

Application filed March 16, 1883. (No model.)

To all whom it may concern:

Be it known that I, IRA C. TERRY, a citizen of the United States, residing at St. Louis and State of Missouri, have invented certain new and useful Improvements in Car-Axle Trucks, of which the following is a specification, reference being had therein to the accompanying drawings.

My improvement consists in constructing a car-truck the cross-beams of which are formed of T-rails, and in so arranging them that the flanges of the rails shall rest against the arch-bar and truss-bar, and with the heads of the rails preferably against each other, although I sometimes place them in the reverse position, or base to base.

Referring to the drawings making a part of this specification, and in which like reference-letters indicate corresponding parts in all the views, Figure 1 is a side elevation of a truck embodying my invention. Fig. 2 is a sectional view on line 2 2 of Fig. 1. Figs. 3 and 4 are detail views. Fig. 5 is a side elevation of a slightly-different form of truck with my invention applied thereto. Fig. 6 is a section on line 6 6 of Fig. 5. Fig. 7 is a side elevation of another modified form of truck, and Fig. 8 is a section on line 8 8 of Fig. 7.

The wheels, axle-boxes, and bearings are of any ordinary or approved construction.

A is the arch-bar. B is the truss-bar. C is the auxiliary arch-bar; D, the draft bar or cord, and G are the cross-beams, which I form of T-rails, with the heads of the rails against each other. The flanges of the rails composing the beams are provided with the holes a b. (Shown in detail in Figs. 3 and 4.) The arch-bar has holes c d, and corresponding holes, e f, are made through the truss-bar, holes c' d' through the auxiliary arch-bar, and holes g and h through the draft-bar. These holes or apertures through the beams and bars are for the passage of two pairs of parallel bolts, E F, by means of which bolts and their nuts x x' the parts are securely clamped together.

Having first drilled the holes through the flanges of the rails and through the arch and truss bars, I place two pairs of the rails at a suitable distance apart to form the beams,

locating them between the arch and truss bars, 50 the bottom of the upper rail, which forms part of the beam, being placed against the arch-bar, and the bottom of the lower rail, which forms the other part of the beam, being placed against the truss-bar, or head against head, and in 55 such position that the holes in the rails and bars will coincide. The bolts E and F are then passed through the holes and are clamped by means of the nuts x x', both bolts and nuts being screw-threaded in the usual manner. If but 60 two rails are used, the bolts are passed through the arch and truss bar only; but if the third rail is used below the auxiliary arch-bar, as in Figs. 5 and 6, the bolts are passed through all the 65 arch and truss bars, and also through the lower or draft bar. I prefer, also, in case the third rail is used, to locate it so that the head of said rail shall bear against the auxiliary arch-bar, as shown. Whether two or three rails are used, the swinging bolster may be 70 readily applied by means of suspended axle-seats on top of the beams, which are secured thereto by riveting or in any other suitable manner; or the trucks may be rigid, and spring-seats may be formed by means of suitable 75 plates between the beams, as shown in Figs. 7 and 8. They may be riveted to the lower rails or the upper rails, or to both.

It will be seen that the parts are securely clamped by bolts on each side of the rails, 80 which are substantially parallel with each other, and which are passed through the flanges of the rails which form the beams, through the truss and arch bars, and are secured by suitable nuts, thus forming a strong, durable, and 85 easily-constructed truck. The bolts bear against the heads of the rails which form the beams; or they are partially sunk in indentations made in the heads of the rails.

In the accompanying drawings I have shown 90 the beams constructed of T-rails head to head, and I prefer to use them in this manner; but I do not wish to limit myself to this form of construction, as I sometimes place them in the reverse position, or base to base, so that the 95 flanged portions of the rails shall be together, instead of the heads.

It is obvious that my invention is applicable

to the style of truck shown in Fig. 1, or to those represented by Figs. 7 and 8.

I am aware that what is known as "channel-iron," and also "angle-iron," have both been used in the construction of car-trucks; but neither has the form, the strength, or the functions of T-iron as beams for a truck, and I do not claim any such forms of iron.

Having thus fully described my invention, what I claim as new, and desire to secure by Letters Patent, is—

1. The combination, in a car-truck, of the beams formed of T-rails with the arch and truss bars, all secured together by parallel bolts passed through or resting in recesses in the flanges on both sides of the beams, substantially as set forth.

2. The cross-beams G, composed of T-rails, placed with the flanges of the rails against the arch and truss bars, said parts being clamped at their ends by means of bolts which are passed through the arch and truss bars, through the flanges of the rails, and which bear against or rest in indentations in the rail-heads, substantially as set forth: 25

In testimony whereof I affix my signature in presence of two witnesses.

IRVING C. TERRY.
